METAL AWNING

Charles F. Moser, Youngstown, Ohio

Application October 31, 1932. Serial No. 640,393

2 Claims. (Cl. 156—15)

This invention relates to metal awnings.

The principal object is to provide an awning of metal that may be attached to the outside of a building to protect a window or a door.

5 A further object is to provide an awning constructed of metal wherein the parts may be assembled, if desired, at the time the same is being attached to the building.

A still further object is to provide novel means 10 for securing the awning to the building and securing together the parts of the awning.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, 20 without departing from the spirit of the invention.

The invention is illustrated in the accompanying drawing, wherein:—

Figure 1 is a perspective view of the awning 25 with a part broken away.

Figure 2 is a perspective view of the awning shown in a modified form.

Figure 3 is an enlarged cross section taken on line 3—3 of Figure 1.

30 Figure 4 is an enlarged cross section taken on line 4—4 of Figure 1.

Figure 5 is an enlarged cross section taken on line 5—5 of Figure 1.

Figure 6 is an enlarged cross section taken 35 on line 6—6 of Figure 2.

Referring to the drawing in detail, it will be seen that numeral 1 denotes an awning top, preferably made of sheet metal. By referring to Figure 5 it will be seen that the awning top 1 at its upper end 2 is provided with a partly opened loop 3. A lower end 4 of a supporting strip 5 is provided with an inturned loop which functions in the partly opened loop 3. An upper end of the supporting strip 5 is provided with an inturned curved edge 6 in order that the same may fit closely to a wall 7. This supporting strip 5 is held in position on the wall 7 by means of screws 8. The awning top 1 is provided with side aprons 9 and an end apron 10. This apron 10 is formed of a downturned portion of the awning top 1.

By referring to Figure 1 it will be seen that these side aprons 9 are formed with an inturned edge 11 in order that the same may be secured 55 to the wall 7.

By referring to Figure 3 it will be seen that the edges 12 are formed with an inturned hook portion 13 into which functions an outturned hook 14 formed from an upper edge of the apron 9.

60 By referring to Figures 1 and 4 it will be seen that the corners formed by the meeting of ends of the apron 10 with the aprons 9 are held in a secured relation to each other by means of inturned and partly closed loops 15 into which functions a clip 16 provided with oppositely disposed inturned hooks.

65 By referring to Figures 2 and 6 it will be seen that the aprons 9 and 10 are provided at lower edges with a box shaped flange 17 which is an integral part of the aprons 9 and 10. It will also be seen that the corner members 18 are held in position by means of a clip 19 functioning on an inturned flange 20 formed on the box shaped flange 17.

70 Having thus described my invention, what I claim is:—

1. In a metal awning formed of parts designed and constructed of interlocking parts so as to be easily and rapidly assembled and taken apart, 80 detachable side aprons for said awning, an end apron for said awning, a box shaped flange formed on bottom edges of said end and side aprons, corner members forming joining means for said box shaped flanges. 85

2. In a metal awning formed of parts designed and constructed of interlocking parts so as to be easily and rapidly assembled and taken apart, detachable side aprons for said awning, an end apron for said awning, a box shaped flange 90 formed on bottom edges of said end and side aprons, corner members forming joining means for said box shaped flanges, an inturned flange formed on said box shaped flange, a clip formed on said corner members and functioning with 95 said inturned flange for the purpose of holding said corner members in position.

CHARLES F. MOSER.
